Primary Examiner — Austin Murphy(74) *Attorney, Agent, or Firm* — Polsinelli PC(57) **CLAIM**

I claim the ornamental design for a mouse and dock, as shown and described.

DESCRIPTION

FIG. 1 is a perspective view of a mouse and dock; FIG. 2 is a perspective view thereof, showing the MOUSE exploded from the dock;

FIG. 3 is a front elevational view of the dock;

FIG. 4 is a rear elevational view of the dock;

FIG. 5 is a left side elevational view of the dock;

FIG. 6 is a right side elevational view of the dock;

FIG. 7 is a top plan view of the dock; and,

FIG. 8 is a bottom plan view of the dock.

Broken lines are for illustrating portions of the mouse and dock which form no part of the claimed design.
